CLAIM

I claim the ornamental design for a case, as shown and described.

DESCRIPTION

FIG. 1 is a front isometric view of a first embodiment of a case;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front isometric view of the case of FIG. 1 in an alternate open configuration; and,

FIG. 9 is a front isometric view of a second embodiment of a case in an open configuration, wherein a closed configuration thereof is depicted in FIGS. 1–7.

The oblique lines in the drawings are meant to represent a highly reflective surface. The long, thin broken lines in the drawings are for the purpose of illustrating portions of the case that form no part of the claimed design. The dot-dash lines indicate stitching on the case as a claimed feature of the case.
